DRAIN BOARD

Thomas J. Little, Jr., Syracuse, N. Y., assignor to
 Easy Washing Machine Corporation, Syracuse,
 N. Y., a corporation of Delaware

Application June 18, 1937, Serial No. 148,975

6 Claims. (Cl. 210—75)

My invention relates to new and useful improvements in laundering machines and relates more particularly to a drain or drip board adapted to be used with a clothes drier or extractor 5 or a drainboard to be used in connection with that type of laundering machine in which an extractor or clothes drying apparatus is mounted on a common base with a washing machine.

In laundering machines of the type wherein a 10 pair of vats are employed, one for containing elements for washing the clothes and the other for containing mechanism for substantially drying the clothes, the washing and drying vats are usually mounted in juxtaposition upon a common 15 base. To prevent drippage of fluid on the floor as the clothes are being transferred from the washing vat to the drying or extractor vat, it has been customary to utilize some form of drainboard between the washing vat and the extractor 20 vat adapted to cause such drippage to drain back into the washing vat.

In addition to preventing drippage of fluid on to the floor as the clothes are transferred from the washer to the extractor, it is desirable to 25 provide means for preventing drippage as the clothes are transferred from an external vessel, such as a laundry tray, to the extractor or from the extractor to the external vessel. Several 30 forms of drainboards have been used to meet these several requirements. One of the most common is to provide a fixed drainboard between the extractor and the washer and utilize the under surface of the cover of the extractor vat as a second drainboard. A second is to provide a single drainboard pivoted on a horizontal 35 axis and movable from a position on one side of the vat to a diametrically opposed position on the opposite side of the vat, as shown in Nelson Patent No. 2,007,112, filed December 8, 1932 and 40 issued July 2, 1935. Still another is to provide a single drainboard rotatable to various circumferential positions with respect to the extractor so that the drainboard may be located with 45 respect to the extractor in the position desired to prevent drippage on the floor. The latter type of drainboard is the most convenient since it may be moved to any circumferential position with respect to the extractor vat and is the least expensive to build. However, it is difficult to 50 support the drainboard on the extractor vat rigidly in position and still enable it to be easily and conveniently rotated about the upper circumferential edge of the vat.

An object of my invention is to provide an 55 inexpensive drainboard structure which is easy

to operate and may be quickly moved from one position to another circumferentially of the extractor vat.

Another object of my invention is to provide a drainboard for the extractor of a laundering machine which may be supported on the upper circumferential edge of the extractor vat rigidly in position and which nevertheless may be easily and quickly rotated to any desired position circumferentially of the vat.

More specifically, my invention contemplates the provision of an extractor vat having a circumferential groove adjacent its upper edge and a down-turned upper lip, and the provision of a drainboard having a plurality of rollers extending into said groove and having a plurality of elements or fingers confined beneath said down-turned lip, whereby the drainboard is rigidly supported in a substantially horizontal position and yet may be quickly and conveniently moved on said rollers so as to extend from the extractor vat in any desired position circumferentially thereof.

Other objects and advantages of my invention will be more apparent from the following description when taken in connection with the accompanying drawing, in which:

Figure 1 is a plan view indicating a laundering machine having a washing vat, and an extractor vat with my novel drainboard structure 30 mounted thereon;

Figure 2 is a view taken on the line 2—2 of Figure 1 showing the drainboard and the extractor, the means by which the drainboard is mounted on the extractor vat and the relative 35 position of the drainboard with respect to the washing vat;

Figure 3 is a view taken on the line 3—3 of Figure 2; and

Figure 4 is a view taken on the line 4—4 of 40 Figure 3.

Although my novel drainboard structure, generally indicated by the numeral 11, is adapted to be used with an extractor mounted separately from a washing machine, it has been shown in 45 use on the extractor vat 12 of a laundering machine. The extractor vat 12 is mounted on a common base, not shown, in juxtaposition to a washing vat 13 containing the usual means, such as an agitator or dolly 14, for washing clothes. The general construction may be similar to that shown, for example, in Nelson Patent No. 2,007,- 50 112, filed December 8, 1932 and issued July 2, 1935.

The extractor vat 12 has mounted therein any 55

suitable means for drying clothes, such as a rotatable perforated basket 15 which, since it does not constitute a part of my present invention, need not be more particularly described. The 5 washing and drying mechanism may be driven by any suitable means and each may be driven separately or both may be driven from a common motor, as is the more usual practice. The extractor vat 12 may have substantially straight 10 vertical side walls and adjacent its upper circumferential edge may be formed a groove or channel 16. The groove 16 extends completely around the circumference of the extractor vat. At its upper circumferential edge, the side walls of the 15 vat are bent and rebent to form an outwardly and downwardly extending lip 17 completely encircling the vat. The groove 16 and the curled lip 17 not only serve to strengthen the upper edge of the vat, but are also adapted to receive 20 elements for supporting the drainboard, as will be later described.

The drainboard 11 comprises a flat plane surface 18, the outer edge of which is curled downward slightly, as indicated at 19, and the inner 25 edge of which is curled upward, as indicated at 21. The inner curled edge extends over the upper circumferential edge or lip of the extractor vat to form a bridge portion 22 to prevent leakage of fluid downward along the sides of the 30 vat. The side edges of the drainboard are provided with upwardly extending flanges 23 which are adapted to confine and direct the flow of fluid on the drainboard surface 18. The drainboard, while it may be die-cast of an aluminum alloy, is 35 preferably a stamping or an iron casting because it may be made more cheaply by either of the latter two methods.

Formed integral with the bottom of the drainboard are a plurality of bosses 24 which are 40 adapted to receive brackets 26 and 27 which may be screwed in or otherwise secured to the bosses. The inner ends of the brackets 26 and 27 are bent upward, as indicated at 28, and serve as a support for rollers 29. The rollers may be made 45 of rubber and may each be provided with a central sleeve 30. The rollers may be mounted on the brackets by means of rivets 31 which serve as shafts for the rollers and with respect to which the sleeves are rotatable. The rollers are supported by the brackets in such position that the 50 centers of the rollers lie on a circle, of which the center of the extractor vat is the center. Each of the rollers lies in the channel or groove 16 which extends circumferentially of the extractor vat.

Extending upward from each of the brackets 55 26 and 27 is a finger 32. The fingers may be integral with the brackets or riveted thereto as indicated at 33. Each of the fingers lies in the downwardly curled lip 17 formed at the upper 60 edge of the extractor and bears against the outer wall of the downwardly curled lip. The combination of the rollers 29 and the fingers 32, spaced around the circumference of the extractor vat holds the drainboard rigidly in position with the 65 drainboard surface 18 slightly inclined downward away from the extractor vat. Further, the rollers, since they lie in the groove 16, serve to support the bridge portion 22 of the drainboard in spaced relation to the curled lip 17 of the vat so 70 that when the drainboard is rotated, the upper curled surface of the lip of the vat is not marred. The drainboard may be easily and conveniently moved on the rollers to extend from the vat in any desired position circumferentially thereof.

75 It will be apparent that I have provided a sim-

ple drainboard structure which may be manufactured at a very reasonable cost, since it may be either a stamping or iron casting, and nevertheless have provided a drainboard structure which may be easily rotated from one position to another about the circumference of the extractor vat. It will further be apparent that various changes and modifications may be made in the form and relation of the parts of my novel drainboard structure and the supporting means therefor without departing from the spirit of my invention as set forth in the appended claims.

I claim:

1. In a machine of the class described, a vat, 15 a drainboard, means extending from the lower side of said drainboard and engaging the vat just below the upper edge thereof for supporting the drainboard in drainboard position with respect to the vat, said means enabling the drainboard to be rotated around the circumference of the vat, said drainboard having an upper drainboard surface terminating in an annular lip extending over the upper edge of said vat, said drainboard being held by said supporting means so that said annular lip is spaced from the upper 25 edge of the vat.

2. In a machine of the class described, the combination of a vat having a groove adjacent the upper edge thereof extending around the vat, and a drainboard having a plurality of rollers supported from the underside of said drainboard and extending into said groove, means for supporting said drainboard in a substantially horizontal plane while enabling the drainboard to be rotated on said rollers to various circumferential positions around the vat, said drainboard having an upper drainboard surface sloping downward away from the vat.

3. In a machine of the class described, the combination of a vat having a groove adjacent the 40 upper edge thereof extending around the vat, and having an outwardly and downwardly extending lip, and a drainboard, means extending from said drainboard for supporting the drainboard in a substantially horizontal plane while enabling the 45 drainboard to be rotated to various circumferential positions with respect to said vat, said means comprising a plurality of rollers supported from said drainboard and extending into said groove and a plurality of elements carried by said drainboard and extending beneath said lip.

4. In a machine of the class described, the combination of a vat having an outwardly and downwardly turned lip extending around the vat at the upper edge thereof and a drainboard, means 55 extending from said drainboard for supporting the drainboard in a substantially horizontal plane while enabling the drainboard to be rotated to various circumferential positions with respect to said vat, said means comprising a plurality of 60 rollers carried by said drainboard and engaging the sidewalls of said vat adjacent the upper edge thereof and a plurality of elements carried by said drainboard and extending beneath said lip.

5. In a machine of the class described, the combination of a vat having a circular groove extending around said vat adjacent the upper edge thereof and a drainboard assembly including a drainboard, means including a plurality of rollers extending from said drainboard assembly for 70 supporting the drainboard in a position extending outward from said vat, said rollers being seated in said groove and enabling the drainboard to be rotated circumferentially of said vat.

6. In a machine of the class described, the 75

combination of a vat having a groove adjacent to the upper edge thereof extending around the vat and having an outwardly and downwardly extending lip, a drainboard, a plurality of fingers 5 extending from said drainboard adapted to engage beneath said outwardly and downwardly extending lip, and a plurality of rollers extend-

ing from said drainboard and seated in said groove, said fingers and rollers being adapted to support the drainboard in a substantially horizontal plane while enabling the drainboard to be rotated to various circumferential positions with respect to said vat. 5

THOMAS J. LITTLE, JR.
